UNITED STATES PATENT OFFICE.

WILLIE DE LANO WHITNEY, OF HOLLEY, NEW YORK.

HARROW-POINT.

1,400,118.

Specification of Letters Patent. Patented Dec. 13, 1921.

Application filed November 8, 1919. Serial No. 336,545.

To all whom it may concern:

Be it known that I, WILLIE DE LANO WHITNEY, a citizen of the United States, residing at Holley, in the county of Orleans and State 5 of New York, have invented a new and useful Harrow-Point, of which the following is a specification.

This invention relates to an improved harrow point or tooth and more particularly to 10 one of the reversible type and improved fastening means therefor.

The invention is in particular, an improvement upon my Patent No. 730,725 of June 9, 1903, and the object thereof is to se- 15 cure greater efficiency in the retention of the tooth or point in position in the clip constituting means for attaching the point to the beam or shank of the harrow or cultivator.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed without departing from the spirit of the invention.

Referring to the drawing:—

30 Figure 1 is a perspective view showing the improved harrow point and fastening means.

Fig. 2 is a vertical sectional view thereof.

Fig. 3 is a vertical sectional view taken on the line 3—3 of Fig. 2, and

35 Fig. 4 is a fragmentary vertical sectional view at right-angles to Fig. 2.

Referring to the drawings in detail, the numeral 5 designates a shank or beam to which the point 6 is adapted to be secured.

40 This point is double ended and of tapering formation at its ends, while the intermediate part is provided with a concave bulge 7, at opposite edges of which are provided recesses 8 the end walls 9 of which extend at 45 right-angles to the inner edge walls thereof.

Communicating with one of the recesses 8 is an intermediate recess 10 of very small length compared to the length of the recesses 8 and extending a distance into the 50 width of the point at its intermediate portion. This construction is designed to co-operate with a clip 11 having a transverse

convex bar 12 to engage the bulge of the point whereby to facilitate the attachment of the point and prevent it from shifting between the bar of the clip and said shank. The clip is in the form of a frame having a transverse portion 13 provided with a threaded aperture for receiving a clamping screw or the like 14 or other suitable co-operating means for exerting pressure between the parts when assembled, while also permitting quick separation of the parts so that the point can be reversed in position when desired. 55 60 65

The clip is further provided with side arms 15 and 16 engaging the recesses 8 so as to prevent turning or vertical displacement of the point in addition to the construction already described. The transverse bar at its 70 inner or convex face adjacent to the arm 15 is provided with an inwardly extending lug 17 preferably formed or cast integral therewith and engaging the recess 10 so as to more securely hold the point in the clip and 75 keep it from slipping vertically or otherwise. Thus, the point can be reversed in position when one end is worn and thereby increase the life and effectiveness of the harrow more than twofold. 80

Having thus described the invention, what is claimed is:—

1. The combination with a clip constituting a fastening member and having a transverse bar; of a double ended point having side recesses receiving the sides of the clip adjacent to said bar, a lug projecting inwardly from the bar adjacent one side, said point having a recess communicating with one of the aforesaid recesses and receiving 85 said lug therein. 90

2. A tooth for cultivating implements having a transverse concave bulge, in combination with a clip constituting a fastening member and having a transverse convex bar to engage said bulge, said tooth having a side recess of relatively small width and a lug projecting inwardly from the bar and engaging said recess, said recess and lug being of rectangular formation. 95

3. A tooth for cultivating implements having pointed ends, said tooth having side recesses, a clip in the form of a frame having a transverse bar engaging the forward face 100

of the tooth, side arms and a connecting portion, clamping means between the connecting portion and the rear face of a shank engaged in the clip in rear of the tooth, said tooth having an auxiliary recess communicating with one of the aforesaid recesses, and a lug carried by the clip and engaging said auxiliary recess.

In testimony that I claim the foregoing as my own, I have hereto affixed my signature 10 in the presence of two witnesses.

WILLIE DE LANO WHITNEY.
